US0D1038738S

(12) **United States Design Patent** (10) **Patent No.:** **US D1,038,738 S**
(45) **Date of Patent:** **** Aug. 13, 2024**

(54) **QUICK ACCESS COVER WITH PANELS FOR CABLE TRAY**

2009/0032651 A1 2/2009 Sayres
2014/0360751 A1 12/2014 De Vis et al.
2019/0052071 A1 2/2019 Henry

(71) Applicant: **Eaton Intelligent Power Limited**,
Pembroke (IE)

* cited by examiner

(72) Inventors: **Bret Eilerman**, Highland, IL (US);
Matthew Thomas Combes, Greenville,
IL (US)

Primary Examiner — Cynthia R Underwood
(74) *Attorney, Agent, or Firm* — Stinson LLP

(73) Assignee: **EATON INTELLIGENT POWER LIMITED**, Dublin (IE)

(57) **CLAIM**

The ornamental design for a quick access cover with panels for cable tray, as shown and described.

DESCRIPTION

(**) Term: **15 Years**

(21) Appl. No.: **29/807,975**

(22) Filed: **Sep. 16, 2021**

(51) LOC (14) Cl. **09-06**

(52) U.S. Cl. **D8/356**
USPC **D8/356, 354, 349, 396, 394, 382;**
D13/155; D24/128

(58) **Field of Classification Search**
USPC **D8/356, 354, 349, 396, 394, 382;**
D13/155; D24/128
CPC **H02G 3/30; H02G 7/12; F16L 3/223**

FIG. 1 is a perspective view of a quick access cover with panels for cable tray;

FIG. 2 is a right elevational view thereof;

FIG. 3 is a top plan view thereof;

FIG. 4 is a front elevational view thereof;

FIG. 5 is a left elevational view thereof;

FIG. 6 is a bottom plan view thereof;

FIG. 7 is a back elevational view thereof;

FIG. 8 is a perspective view of a panel shown enlarged and removed from the quick access cover with panels for cable tray of FIG. 1;

FIG. 9 is a front elevational view thereof;

FIG. 10 a top plan view thereof;

FIG. 11 is a right elevational view thereof;

FIG. 12 is a back elevational view thereof;

FIG. 13 is a bottom plan view thereof;

FIG. 14 is a left elevational view of thereof;

FIG. 15 is a perspective view of FIG. 1 shown with the panels removed;

FIG. 16 is a right elevational view thereof;

FIG. 17 is a top plan view thereof;

FIG. 18 is a front elevational view thereof;

FIG. 19 is a left elevational view thereof;

FIG. 20 is a bottom plan view thereof; and,

FIG. 21 is a back elevational view thereof.
